ATTORNEY

UNITED STATES PATENT OFFICE.

ISIDOR SHULMAN, OF NEW YORK, N. Y.

DESIGN FOR A PENCIL BOX OR SIMILAR ARTICLE.

Application filed March 12, 1925. Serial No. 12,691. Term of patent 7 years.

To all whom it may concern:

Be it known that I, ISIDOR SHULMAN, a citizen of the United States of America, residing at New York city, county, and State of New York, have invented a new, original, and ornamental Design for a Pencil Box or Similar Article, of which the following is a specification, reference being had to the accompanying drawing, forming part hereof, in which—

Figure 1 illustrates a top plan view of a pencil box or similar article showing my new design and Figure 2 a side elevation thereof.

I claim:

The ornamental design for a pencil box or similar article as shown.

Signed at New York city, N. Y. this 5th day of March, 1925.

ISIDOR SHULMAN.

Witnesses:

MAURICE BLOCH,
JOHN J. LYNCH.
